COIN DISPENSER

John Bauer, Sunnyside, and Max Grau, New York, N. Y.

Application March 26, 1936, Serial No. 70,917

2 Claims. (Cl. 133—5)

This invention relates generally to a coin dispenser adapted to be inserted within a lady's handbag, and more specifically to a coin dispenser wherein the feeding slot is within the handbag and the extracting receptacle is external to the handbag.

The main object of the invention resides in the provision of a coin dispenser whereby coins may be extracted from a position external to the handbag or other object in which the said dispenser is secured.

Another object of the invention resides in the provision of a coin dispenser which is loaded within a handbag or a muff, without the necessity for the removal of any parts.

A further object of the invention is the provision of a coin dispenser of the nature described wherein one coin at a time is capable of being removed upon the application of pressure.

These objects and other incidental ends and advantages of the invention will hereinafter appear in the progress of the disclosure and as pointed out in the appended claims.

Accompanying this specification is a drawing showing preferred forms of the invention, and wherein corresponding reference characters designate corresponding parts throughout the several views.

In accordance with the drawing Figure 1 is a view in perspective showing a dispenser secured in a lady's handbag.

Figure 2 is a plan view of the coin dispenser shown in Figure 1 with the cover thereof removed.

Figure 3 is a sectional view of Figure 2 along the plane 3—3 thereof, the said Figure 3 showing, however, the cover member in transverse section.

Figure 4 is a fragmentary plan view inverted of the upper vertical leg shown in Figure 2 and depicting a gravity stopping device.

Figure 5 is a fragmentary view in perspective showing a lady's handbag with a coin dispenser of another shape mounted therein.

In accordance with the invention, numeral 10 represents a handbag showing a coin dispenser 45 therein mounted, the feeding portion of the coin dispenser being within the handbag while the coin extracting receptacle penetrates an edge of the handbag. The dispenser is preferably affixed to the handbag between the lining and the inner 50 facing of the body or leather portions thereof by any means of affixation, said means, however, not being shown on the drawing.

The coin dispenser comprises a continuous and enclosed flat channel having a feeding and upper 55 vertical leg, a communicating magazine leg

obliquely disposed thereto and a downwardly disposed dispensing leg.

The dispenser is preferably comprised of sheet metal having a lower portion and a cover member therefor. The lower portion and cover members are provided with parallel and opposing walls or flanges to define the width and thickness of the communicating channels. From Figure 2, the lower portion of the dispenser is shown as comprised of a single sheet of metal having a feeding and upper vertical leg 15, a communicating magazine leg 17 downwardly and obliquely disposed thereto, the said leg 17 reversing itself as at 28 and proceeding inwardly and obliquely as at 21. A vertically disposed dispensing leg 29 is 10 in communication with channel 27. Legs 15, 17, 28, 21 and 29 are defined by lateral walls or flanges 41 and 42. Walls 41' on the sheet metal lower portion of the coin dispenser serve respectively as one of the limiting walls of legs 17, 28, 21 and 29. Dispensing leg 29 is rearwardly offset 15 in a plane parallel to the plane of the sheet metal lower portion in order that slide 30 springably returnable therein has its upper surface on the same plane with the legs 21. Slide 30 near the upper end is provided with a slot 31 and an upwardly protruding lug 32 at the base of said slot. A spring 33 is connected to lug 32 and to the wall 41' forming the upper limit of leg 29. Along wall 41 of leg 29 and intermediate the ends thereof is affixed a stop 35, the said stop controlling the maximum outstretched position of slide 30 by engaging a corner lug 34 of the slide. The said stop 35 functions also to keep slide 30 against the surface of leg 29. At the lower end of slide 30, which normally projects beyond the lower edge of leg 29, is provided a coin stop having a spaced upper narrow wall 37, a lower end wall 38 and an outer side wall 36 slidable along wall 41 of leg 29. The lower wall of the stop is served by 40 slide 30, the said slide 30 at the lower inner corner being cut out in the form of a curve 40. By pulling out slide 30 as shown in dot and dash lines on Figure 2, the coin may be removed.

Between the vertically disposed feeding leg 15 45 and oblique leg 17 are means to prevent escape of coins when the device is inverted. Between the inner edges of legs 15 and 17 is an extension 19. A pin 20 is affixed to extension 19 and carries a pivoting small curved arm 21. The limits of 50 movement of the arm 21 are provided by the end of wall 42 in leg 15 and a wall 22 on the inner edge of extension 19. Another pin 23 is affixed to leg 15 near the outer wall 41 and carries a pivoting and larger arm 24. Wall 41 is broken as 55

at 26 to permit arm 24 to rotate and also to serve as a stop when said arm is in inverted position.

16 indicates the feeding entrance to leg 15 and may be rearwardly offset for a distance to give this portion added width for receiving a few coins at a time.

The cover member of the device described is shown on Figure 1 with engaging fingers attached to the cover member. The cover member is provided with counterparts 15', 17', 28', 27' and 30'.

Where the coin slot is desired to be manipulated from a side of a handbag or other receptacle, the dispensing leg may be arranged as shown in Figure 5. The oblique leg 17" is in communication with an oblique dispensing leg 45 by an intermediate leg 44.

It is to be observed that the slide 30 at the upper part of the lateral inner edge is provided with a wall 38' and an end stop thereof 38" which stops the descent of coins 43 from leg 27 when the slide 30 is in outstretched position. The end stop 38" prevents the passage of more than one coin onto slide 30 as shown in Figure 2. When the slide 30 is in maximum outstretched position as shown in dot and dash lines on Figure 2, the coin 43 is in position to be removed by the fingers. In order that another coin be removed the slide 30 must be released for further feeding. Thus one coin at a time is capable of being withdrawn from the coin slot 37. The outer side wall 36 is provided with an offset portion 47 along the width thereof and opposite to an indented portion 46 of wall 42 between the outer walls of legs 27 and 29. Thus from an inspection of Figure 2 the lowermost coin when the slide 30 is in a normal position is held in place between offset 47 and indentation 46, the distance between the said two parts being less than the diameter of the coin. However, when the slide 30 is in the maximum or outstretched position the alignment between offset 47 and indentation 46 is broken, thereby permitting the coin to drop down to end wall 38.

Thus has been described, a coin dispenser,

which is fed from the interior of a handbag or other receptacle. The dispenser has a magazine for coins, so that when fed, a series of coins are in readiness to be removed without opening the handbag or receptacle.

We wish it understood that minor changes and variations in the integration, construction and position of the several parts, together with the material thereof, may all be resorted to without departing from the spirit of the invention and the scope of the appended claims.

We claim:

1. A coin dispenser comprising a continuous and enclosed channel having a feeding and upper vertical leg, a communicating magazine leg obliquely disposed thereto, a downwardly disposed and rearwardly offset dispensing leg, a springably returnably mounted slide within the said dispensing leg, the surface of said slide being co-planar with the surface of the feeding and communicating legs, a coin receptacle affixed to the said slide, means to prevent escape of coins between the feeding and upper vertical leg and the magazine leg when the dispenser is inverted.

2. A coin dispenser comprising a continuous and enclosed channel having a feeding and upper vertical leg, a communicating magazine leg obliquely disposed thereto, a downwardly disposed and rearwardly offset dispensing leg, a springably returnably mounted slide within the said dispensing leg, the surface of said slide being co-planar with the surface of the feeding and communicating legs, a coin receptacle affixed to the said slide, means to prevent escape of coins between the feeding and upper vertical leg and the magazine leg when the dispenser is inverted and a stopping member along an edge of the said slide to prevent passage of coins from the magazine leg to the coin receptacle when the slide is withdrawn to maximum outstretched position for the removal of a coin.

JOHN BAUER.
MAX GRAU.
